UNITED STATES PATENT OFFICE.

JOHN J. GILLESPIE, OF BOSTON, MASSACHUSETTS, ASSIGNOR TO UNITED SHOE MACHINERY COMPANY, OF PATERSON, NEW JERSEY, A CORPORATION OF NEW JERSEY.

STAMPING-MACHINE.

1,102,039.

Specification of Letters Patent. Patented June 30, 1914.

Application filed October 7, 1908. Serial No. 456,572.

To all whom it may concern:

Be it known that I, JOHN J. GILLESPIE, a citizen of the United States, residing at Boston, in the county of Suffolk and Commonwealth of Massachusetts, have invented 5 certain Improvements in Stamping - Machines, of which the following description, in connection with the accompanying drawings, is a specification, like reference characters on the drawings indicating like parts in the several figures.

This invention relates to presses and other machines for operating upon shoes and other articles and it is herein shown as embodied in a shoe stamping machine. These 15 machines are employed for stamping trade or other marks upon the bottoms of shoes. In many instances the manufacturer desires to stamp the shoe bottom in a plurality of 20 places—as, for example, to stamp a trademark or name upon the tread face of the heel and a price or other mark upon the tread face of the shank or other portion of the sole. It is, therefore, frequently necessary 25 to change from one marking die to another in operating on a single shoe and in this operation much time is lost, particularly where it is necessary for the operator to employ both hands in bringing a new die 30 into stamping position. Heretofore it has been the practice to mount a number of marking dies in a rotatable turret carried in a reciprocating head and to provide a spring actuated plunger for locking the turret with one or other of the dies in the 35 stamping position. This arrangement makes it necessary for the operator to use one hand for retracting the locking plunger and the other to turn the turret so as to bring the 40 desired die into position.

With these conditions in view it is an object of the present invention to provide an automatic device for releasing the turret during a convenient interval in the cycle of 45 the stamping machine and so afford the operator opportunity to set a new die in place with one hand while the other is left free for the manipulation of the shoe being operated upon. Such an arrangement is 50 particularly advantageous in connection with a novel work supporting device having provision for adjustment through definite predetermined distances so as to support either the heel or the sole of a shoe at

substantially the same altitude and in the 55 same relation to the stamping head of the machine. Such a work support, separately considered, forms the subject-matter of United States Letter Patent No. 1,022,412, granted April 9, 1912, on divisional application Serial No. 526,395 filed November 5, 1909, but its use in combination with the automatic releasing device, above-mentioned, presents many advantageous and 60 novel features and the combination is, therefore, within the scope of the present application. One of the advantages arising from the combination of the automatic releasing device with the novel work support is that the operator is thereby enabled with one 65 hand to set the turret while with the other hand the work support may be adjusted in accordance with the marking die just brought into position.

Another feature of this invention consists 75 in the construction and arrangement of the turret and the means associated therewith for automatically unlocking it after each impression stroke. As herein shown this mechanism comprises the usual locking plunger coöperating with recesses in the turret and means to retract the plunger at a predetermined point in the stroke of the turret such means being located upon a convenient 80 part of the machine frame and operating to 85 retract the plunger as the turret reaches a certain point in its stroke, hold the plunger retracted for a definite period, during which the turret may be turned and a new stamp may be set, and release it at the proper time 90 whereby the turret is again locked.

As herein shown the locking plunger is forked at its outer end and carries a transverse pin extending between the two forked portions thereof. A fixed arm provided 95 with a plunger retracting member mounted on its lower end projects downwardly from the machine frame between the forks of the plunger and inside the transverse pin, in such a position that the plunger retracting 100 member is normally projected into the path of the transverse pin as the plunger and turret are reciprocated.

When the turret is lowered for the impression stroke the plunger retracting member is forced back and permits the pin to pass but when the turret is raised the pin engages the plunger retracting member and

forces it out, being itself at the same time moved outwardly by the coaction between the two, thus drawing the plunger out of engagement with its recess and permitting the 5 turret to be set in a new position. In some cases it is found that the automatic means for unlocking the turret does not allow the operator sufficient time to set a new stamp and accordingly a releasing device has been 10 devised which is designed to be operated by a treadle. One of the machines in which it is intended to use this releasing device is arranged to make a complete stroke and then stop with the turret in its highest position. 15 The treadle actuated releasing means are, accordingly, so located that at the top of the stroke there exists an operative relation between the different members so that the turret can be unlocked at this point and 20 these means, located partly on the machine frame and partly on the reciprocating turret-carrying head comprise a plunger retracting member mounted on the machine frame to permit of a limited motion under 25 the actuation of the treadle and a locking plunger moving with the turret and carried therewith into operative relation with the treadle actuated plunger retracting member. More specifically this releasing device 30 comprises a lever pivoted on the machine frame, adapted to be actuated by the treadle and having formed thereon a wedge shaped cam surface, and mounted on the turret-carrying head is the usual locking plunger, 35 shouldered toward the turret for engagement with the wedge cam whereby a downward motion of the lever retracts the plunger and leaves the turret free for adjustment. The manually actuated releasing device 40 just described is designed for use either as supplementary to the automatic releasing means and operating on the same locking plunger or the automatic releasing means may be dispensed with and the manual releasing means used alone. The combination 45 of the two results in a convenient machine adapted for efficient use by either a fast or slow operator. A novel means for holding the stamps in the turret has also been provided 50 which consists broadly of a draw bolt adapted to clamp the shank of the stamp within the body of the turret. A hole is drilled into the face of the turret so as to intersect each of the radial openings for 55 the shanks of the stamps and pass through one side thereof. The draw bolt is provided with a recess so located that when the bolt is in its extreme inner position the sides of the recess exactly coincide with the walls 60 of the opening for the shank, forming a continuous surface therewith. The outer end of the bolt is screw threaded and provided with a nut which draws out on the bolt and holds the shank tightly in the body 65 of the turret. In the old form of machine

in which the shanks of the stamps were screwed into the body of the turret a whole turret was often made useless by stripping the thread of one stamp whereas in the improved form there is no liability of damaging 70 the turret.

These and other features of the invention, including certain details of construction and arrangements of parts, will be explained in connection with the following description of a preferred embodiment of the invention and will be pointed out in the claims. 75

In the drawings: Figure 1 is a side elevation of a bottom stamping machine embodying the present invention. This machine is in its general construction and operation essentially similar to a machine shown in United States Letters Patent No. 1,028,567, granted June 4, 1912 on an application filed by Gordon and Topham Serial No. 186,368. Fig. 2 is a section on approximately the line 2—2 of Fig. 4. Fig. 3 is a perspective view of the shoe supporting means. Figs. 4 and 5 show the shoe supporting means and the stamp in different adjusted positions for marking the heel and sole of a shoe, respectively. Fig. 6 is a perspective view of the turret and the means associated therewith for automatically unlocking it after each impression stroke. Fig. 7 is a detail of the same. Fig. 8 is a fragmentary section on the line 8—8 of Fig. 6 showing means for holding the stamps in the turret. Fig. 9 is a perspective view of 100 a turret releasing device which can be used as a supplement to or independently of the means shown in Fig. 6.

The machine comprises a wheel 2 adapted to carry a plurality of stamps 3, 4 for the heel and sole, respectively, together with suitable means for actuating the wheel toward the work-supporting means located below it. The work-supporting means comprises, in accordance with one embodiment 110 of this invention, a base 5 adapted to rest upon a post 6 and sustaining means therefor, which may be like that shown in said patent last mentioned and adapted to yield for slight variations in the thickness of the 115 work or it may be of any other suitable type. The base 5 has, at one side of the line of pressure applied by the stamp, ears 7 between which is pivoted a laterally projecting arm 8 from a spindle guide 10 in which the 120 work-supporting spindle 12 is arranged for adjustment. A pivot pin 15 projects upwardly from the base and holds in assembled relation a plurality of superposed blocks 16 adapted to swing from and toward a position in alignment with or vertically under the spindle 12 where they form auxiliary rests for the spindle. Each of these blocks is provided with a spring-pressed plunger 18 adapted to bear on one or the other of the 130

two beveled surfaces 19 and 20 of the pin 15. These plungers, engaging and beveled faces of the pin, hold the swinging blocks normally in one or the other of two definite positions and when a block is moved slightly past the center in one or the other direction the plungers will continue that movement and force the block fully to the definite position which it is approaching. Each block except the bottom one is provided with a depending stud indicated at 22 adapted to engage a recess 23 in the adjacent face of the next lower block. The recesses are so shaped that when any block except the last block is turned from its inoperative position toward its operative or spindle-raising position all the blocks below it are also compelled to turn in that direction. When any of the blocks are engaged and turned toward inoperative position all the blocks above it are compelled to move with the block to which the turning force is applied. Limiting studs 24, 25 are arranged to stop the lower block in its two positions and the engagement of the pins 22 in the recesses 23 causes the other blocks to be stopped in alignment with the bottom block. The blocks or part of them are or may be proportioned in thickness to the standard heights of heels so that different groups of them will produce different adjustments in the height of the spindle according to the standard height of the heel on the shoes being stamped. The number of the blocks and the thickness or relative thickness of the several parts may be varied as conditions may require.

In the use of the invention the shoe may be applied to the spindle as indicated in Fig. 4 for stamping the tread face of the heel. Then, while the stamp-carrying turret is raised the spindle with its guide may be tipped, as shown in Fig. 3, to raise the spindle and give access to the blocks, whereupon the operator will engage as many of the blocks as are required to compensate for the difference in thickness of the sole and the particular heel of the shoe being stamped and will swing those blocks into their operative position under the spindle. The spindle guide will then be tipped back to its upright position and in this movement the spindle, after contacting with the upper face of the top block in operative position, will be raised to elevate the work to the altitude in which the tread face of the sole to be stamped is in the same or substantially the same relation to the stamp as was the tread face of the heel. In shifting the blocks toward their operative position it is only necessary to engage the top of the blocks which it is desired to use, because the pins 22 compel each of the blocks below the top one to move with that one. It is unnecessary for the operator to restrain the upper blocks

from moving because the spring plungers 18 by their engagement with the inclined face of the pin 15 holds those blocks from movement. Similarly when moving the blocks to their inoperative position it is only necessary to engage the lowest block which is to be turned and all the others are compelled to turn with it. 70

In Fig. 6 is shown the turret 2 carrying the various stamps 3 and provided in one side with a series of recesses 28, one recess corresponding with each stamp, and with these recesses there co-operates the locking plunger 27 properly bushed and slidingly mounted in one arm of the turret-carrying head 9, the inner end of the locking plunger and the recesses being correspondingly tapered. The locking plunger 27 is normally urged toward the turret by the spring 13 to enter one of the recesses and thus hold 85 the corresponding stamp in the proper position for stamping. On the outer end of the locking plunger 27 is mounted, in any suitable manner, the forked member 29 carrying between the outer ends of its fork the 90 transverse pin 30. Mounted upon a convenient stationary part of the machine is the downwardly projecting arm 26 having a reduced portion arranged to slide freely between the forks of the member 29 as the 95 turret and locking mechanism are reciprocated. This arm at its lower end is provided with a slot in which is pivotally mounted the wedge shaped cam member 31, the pivot being approximately at its vertex, as shown and a spring 32 tending normally to hold the wedge shaped member projecting into the path of the transverse pin 30. 100

It will be apparent from inspection of Fig. 7 that as the turret is lowered carrying with it the locking mechanism the pin 30 will ride down the inclined face of the wedge 31 and then the wedge will yield into its slot thus permitting the pin to pass 110 without being deflected from its path or disturbing the locking plunger 27. On the other hand, when the turret is moving away from the work and the pin 30 travels upwardly it engages the lower face of the 115 wedge 31 swinging it outwardly about its pivot, as shown by the dotted lines in Fig. 7, and moving with it away from the turret thus withdrawing the locking plunger 27 and leaving the turret free to be turned 120 by the operator. At the upper limit of the stroke the pin 30 slides off the wedge shaped member above it and the plunger 27 is returned to engage the turret. By varying the proportions slightly it is sometimes expedient to prevent this final disengagement of plunger and wedge shaped member so that the plunger is held retracted at the upper limit of the stroke and the turret left 125 free to turn until the machine is again start- 130

ed when on the downward motion of the turret the plunger will again perform its function.

In Fig. 9 is shown a form of turret releasing device which is adapted to be operated by means of a treadle, when, for any reason more time is desired to set the turret than is allowed by the automatic releasing device described above. In this construction a portion of the plunger 27 is reduced in diameter forming the shoulder 33 with which coöperates the forked wedge shaped cam 34, formed on a lever 35 pivoted at one end by a pin 40 to a stationary arm 26' 10 which latter is carried by a suitable part of the machine frame. At its outer end the lever 35 is connected through a link 38 to the treadle 39 and a spring 37 is provided which normally holds the treadle and lever 15 in their upper position. In this construction the turret is released in its upper position by the operator when the treadle is depressed, the lever 35 and the wedge cam 34 carried thereby moving downwardly so 20 that the wedge faces of the forked cam 34 retract the locking plunger 27. This leaves the turret free to turn so long as the treadle is depressed and the turret remains in its upper position while on releasing 25 the treadle, the spring 37 instantly disengages the cam 34 from the shoulder 33 allowing the plunger to lock the turret. In Fig. 9 the turret carrying plunger 9 is represented as in its upper position, the plunger and wedge cam being in operative relation. It will be clear that when the turret starts to move downwardly for the impression stroke the plunger 27 will move beyond the reach of the wedge cam 34, or out of 30 engagement therewith if the treadle is depressed, so that there is no possibility of a stamp reaching the work while the turret is unlocked even if the operator forgets to release the treadle. As already stated 35 the manually operated releasing device may be used with or without the automatic releasing means shown in Fig. 6.

The improved means for holding the stamps in the turret is illustrated in Fig. 8 40 where 3^a represents the shank of one of the stamps 3 set in a radially drilled hole in the turret 2. Bolt holes in this case, but not necessarily, coinciding with the locking recesses 28, are drilled into the side of the turret 45 so as to intersect each radial shank hole and pass through one side thereof. Each draw bolt 50 is provided with a recess 51 on one side so located that when the bolt is in its extreme inner position the sides of 50 the recess exactly coincide with the walls of the radial shank hole and the stamp may be withdrawn or inserted without obstruction. The outer end of each draw bolt is threaded and provided with a nut 52 by 55 which the recess in the bolt may be drawn

slightly out of line with radial shank hole, thereby locking the shank of a stamp firmly in the turret.

Having explained the nature of this invention and described a preferred construction embodying the same, I claim as new and desire to secure by Letters Patent of the United States:—

1. A shoe stamping machine having, in combination, a stamp for marking the tread face of the heel of a shoe and a stamp for marking the tread face of the sole of a shoe and a shoe support comprising a spindle and spindle supporting means having a plurality of supporting faces any one of which may be rendered operative by a single movement to effect a definite adjustment of the spindle to compensate for the difference in thickness of the sole and heel. 75

2. A shoe stamping machine having, in combination, a stamp for marking the tread face of the heel of a shoe and stamp for marking the tread face of the sole of a shoe and a shoe support comprising a spindle and spindle supporting means having a plurality of supporting faces any one of which may be rendered operative by a single movement to effect different definite adjustments of the spindle proportioned to the different heights of heel to lower the spindle a distance equal to the difference in the thickness of the sole and heel. 80

3. A shoe stamping machine having, in combination, a stamp for marking the tread face of the heel of a shoe and a stamp for marking the tread face of the sole of a shoe, power actuating means for said stamps, and a shoe support comprising a spindle and spindle supporting means comprising a base plate, a pivoted guide in which the spindle 100 is endwise movable and by which the spindle can be tipped from and toward the base plate and supporting blocks carried by the base plate and movable separately or in groups from and toward position to support the spindle to compensate for the difference in thickness of the sole and heel. 105

4. A shoe stamping machine having, in combination, a stamp for marking the tread face of the heel of a shoe and a stamp for marking the tread face of the sole of a shoe, power actuating means for said stamps, and a shoe support comprising a spindle and spindle supporting means arranged to permit by a single movement a definite adjustment of the spindle to be made to compensate for the difference in thickness of the sole and heel, and a spindle guide in which the spindle is movable endwise and in which the spindle supporting means is inclosed 115 and is movable transversely of the spindle. 120

5. A shoe stamping machine having, in combination, a stamp for marking the tread face of the heel of a shoe and a stamp for marking the tread face of the sole of a shoe, 125

- power actuating means for said stamps, and a shoe support comprising a spindle and spindle supporting means including a carrier adapted to yield for slight variations in thickness of the work, and an adjusting block movable into and out of an operative position between the carrier and the spindle to compensate approximately for the difference in thickness of the sole and heel.
10. 6. A shoe stamping machine having, in combination, a stamp for marking the tread face of the heel of a shoe and a stamp for marking the tread face of the sole of a shoe, a shoe support comprising a spindle and a spindle supporting block movable toward and from position to rest the spindle, and a spring pressed plunger carried by the block to engage coöperating fixed faces for definitely locating the positions of the block, 20 and power actuating means for relatively moving said stamps and support.
7. A machine of the class described, having in combination, a stamp carrier having a stamp for marking thin stock and a stamp for marking thick stock, a stock supporting spindle, means for resting the spindle to determine its height when thick stock is to be stamped, a block arranged to be positioned under the spindle to change its 30 height when thin stock is to be stamped, and power actuated means for relatively moving said spindle and stamps.
8. A shoe stamping machine having, in combination, a rotatable turret carrying a plurality of stamps for marking a shoe and provided with a series of recesses each one corresponding with one of the stamps, an axially extending locking plunger adapted to engage any one of said recesses, means 35 for vertically moving said turret, and means automatically operated during the upward movement of said turret to retract said locking plunger whereby the turret is left free to rotate.
40. 9. A shoe stamping machine having, in combination, a rotatable turret carrying a plurality of stamps for marking a shoe and provided with a series of recesses in one of its side faces each one corresponding with one of the stamps, an axially extending locking plunger adapted to engage any one of said recesses, means for moving said turret toward or from the work, and means whereby said locking plunger is retracted 45 at a predetermined point in the movement of said turret, whereby the turret is left free to rotate.
50. 10. A shoe stamping machine having, in combination, a movable head, a die-carrying turret mounted therein for turning movement about a transverse axis and having recesses formed in one of its side faces, a locking plunger movable with said head and also independently movable for engagement with one of said recesses, and means actuated by the movement of said plunger relatively thereto for automatically retracting said plunger to release the turret.
55. 11. A shoe stamping machine having, in combination, an adjustable turret, and a locking device therefor, together with means acting on said locking device for automatically unlocking said turret at a predetermined point and means independent of the automatic means for manually unlocking the 60 turret.
60. 12. A shoe stamping machine having, in combination, an adjustable turret and a locking device therefor, together with automatically operating means acting on said locking device for unlocking said turret during the return stroke and independent manually operated means for unlocking said turret at the end of the return stroke.
65. 13. A shoe stamping machine having, in combination, a turret carrying a plurality of stamps for marking a shoe, and locking means therefor, said stamps being retained in radial holes in the turret and a draw bolt extending transversely of the turret for 65 clamping each stamp in the turret, the transverse holes for the draw bolts also coöperating with the locking means for the turret.
70. 14. A shoe stamping machine having, in combination, a movable head, a turret 95 mounted therein, a locking plunger for the turret, a fork carried thereby, a pin extending between the arms of said fork, and a movable cam piece constructed and arranged to pass between the arms of said fork and 100 retract said plunger on movement of said pin relatively thereto in one direction.
75. 15. A shoe stamping machine having, in combination, an adjustable turret, a locking device therefor, means for automatically unlocking said turret, and separate means under the control of the operator and acting on said locking device when it is in engagement with the turret to unlock said turret.
80. In testimony whereof I have signed my 110 name to this specification in the presence of two subscribing witnesses.

It is hereby certified that in Letters Patent No. 1,102,039, granted June 30, 1914, upon the application of John J. Gillespie, of Boston, Massachusetts, for an improvement in "Stamping-Machines," an error appears in the printed specification requiring correction as follows: Page 2, lines 104 and 107, for the word "wheel" read *turret*; and that the said Letters Patent should be read with this correction therein that the same may conform to the record of the case in the Patent Office.

Signed and sealed this 6th day of October, A. D., 1914.

[SEAL.]

R. F. WHITEHEAD,

Acting Commissioner of Patents.
